(57) **CLAIM**

The ornamental design for a diffuser with crystal drawer, as shown and described.

DESCRIPTION

FIG. 1 is an isometric view of a diffuser with crystal drawer illustrating my new design;

FIG. 2 is a front elevation view thereof;

FIG. 3 is a back elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken lines showing control buttons in FIGS. 1, 2, 4, 5 and 7, supporting legs in FIGS. 2 through 5 and 7, a cord receptacle in FIGS. 3 and 7, and a bottom vent and circular element connecting the supporting legs in FIG. 7 are for the purpose of illustrating portions of the diffuser with crystal drawer that form no part of the claimed design. The broken lines showing crystals visible through the drawers in FIGS. 1 through 6 are for the purpose of illustrating environmental structure that form no part of the claimed design.
